(57) **CLAIM**

The ornamental design for a massage ball, as shown and described.

DESCRIPTION

FIG. 1 is a front, left and top perspective view of a massage ball showing my design.

FIG. 2 is a rear, right and bottom perspective view of a massage ball showing my design.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof.

FIG. 8 is a bottom plan view thereof; and,

FIG. 9 is an exploded front perspective view showing the components of the case separated for clarity of disclosure. The broken lines shown in the figures are for the purpose of illustrating portions of the massage ball, which form no part of the claimed design.
